UNITED STATES PATENT OFFICE.

WILLIAM A. HINKLE AND FRANKLIN C. JEFFERY, OF GALVESTON, TEXAS.

DOOR-CHECK.

SPECIFICATION forming part of Letters Patent No. 355,080, dated December 28, 1886.

Application filed October 5, 1886. Serial No. 215,363. (No model.)

To all whom it may concern:

Be it known that we, WILLIAM A. HINKLE and FRANKLIN C. JEFFERY, both of Galveston, in the county of Galveston and State of 5 Texas, have invented a new and Improved Door-Check, of which the following is a specification, reference being had to the annexed drawings, forming a part thereof, in which—

Figure 1 is a perspective view showing the 10 application of our improved door-check. Fig. 2 is a longitudinal section showing the door partly open, and Fig. 3 is a longitudinal section showing the door fully opened and held in position by the door-check.

15 Similar letters of reference indicate corresponding parts in all the views.

The object of our invention is to provide a simple and efficient device for arresting the motion of a door while being opened and for 20 fastening it in an open position.

Our invention consists in a slotted plate provided at one end with a buffer for arresting the door, and having in the walls of the longitudinal slot series of diagonal slots, in combination with a counterweighted latch provided with trunnions received in the diagonal slots, all as hereinafter more fully described.

The base-plate A is provided with a longitudinal slot, B, extending throughout the greater 30 portion of its length, and has at one end an arm, C, projecting at right angles with the plate, with a chamber, a, in its vertical face for receiving the hemispherical elastic buffer D. In opposite walls of the slot B of the frame 35 A are formed series of diagonal slots b, inclined away from the buffer D, and to the slot B is fitted a latch, E, having on opposite edges thereof, near its mid-length, trunnions c, which may be placed in different pairs of diagonal 40 slots b, according to the thickness of the door in connection with which the check is to be used. The end of the latch E nearest the buffer D is apertured to reduce its weight,

while the opposite end is made solid and of sufficient weight to overbalance the apertured 45 end, so that normally the apertured end of the latch projects above the upper surface of the plate A and into the path of the door F, in connection with which the stop is used.

The door-stop is secured to the floor with 50 the buffer D at the point where it is desired to arrest the door when opened, and the trunnions of the latch E are placed in a pair of the slots b, so as to leave a space between the end of the latch and the buffer B about equal to 55 the thickness of the door. When the door is opened, it glides over the latch E, depressing its lighter end and raising its weighted end, and when the door has passed the latch the lighter end of the latch rises in front of the 60 edge of the door, as shown in Figs. 1 and 3, and holds the door in its open position. When it is desired to close the door, the latch E is depressed by the foot.

The latch is operated by gravity and requires no springs. It is therefore inexpensive in its manufacture, and not liable to derangement. As the check is secured to the floor instead of the base-board, as is usual, it may be employed for holding the door open at any desired point. 70

Having thus fully described our invention, we claim as new and desire to secure by Letters Patent—

The combination, with the plate A, provided 75 with the longitudinal slot B, the oblique slots b, and the arm C, of the counterweighted latch E, provided with trunnions c, adapted to be received in the diagonal slots b, substantially as described.

WILLIAM A. HINKLE.
FRANKLIN C. JEFFERY.
